UNITED STATES PATENT OFFICE.

JOHN G. RIDOUT, OF BALTIMORE, MARYLAND.

DESIGN FOR A FRUIT-SPOON.

41,832.

Specification for Design.

Patented Oct. 10, 1911.

Application filed May 12, 1911. Serial No. 626,862. Term of patent 7 years.

To all whom it may concern:

Be it known that I, JOHN G. RIDOUT, a citizen of the United States, residing at Baltimore city, Maryland, have invented a new, original, and ornamental Design for Fruit-Spoons, of which the following is a specification, reference being had to the accompanying drawing, forming a part thereof.

The figure is a perspective view of a fruit spoon, showing my new design.

I claim:

The ornamental design for a fruit spoon, as shown.

J. G. RIDOUT.

Witnesses:

WALTER MANN,
H. C. KAUFMAN.
